UNITED STATES PATENT OFFICE.

ALBERT ERICKSON, OF CHICAGO, ILLINOIS, ASSIGNOR TO SPLITDORF ELECTRICAL COMPANY, OF NEWARK, NEW JERSEY.

IGNITION APPARATUS.

1,401,058.

Specification of Letters Patent.

Patented Dec. 20, 1921.

Application filed November 19, 1919. Serial No. 339,081.

To all whom it may concern:

Be it known that I, ALBERT ERICKSON, a citizen of the United States, residing at Chicago, in the county of Cook, State of Illinois, have invented certain new and useful Improvements in Ignition Apparatus, of which the following is a description, reference being had to the accompanying drawing and to the figures of reference marked 10 thereon.

My invention relates to ignition apparatus in which the ignition generator is of the oscillating type and which supplies current to electrodes in an engine cylinder, one 15 of which is adapted to be moved to introduce a spark gap substantially co-incident with the time of generation of maximum current by the ignition generator.

It is the principal object of my invention 20 to provide a generator which will deliver its maximum current at a suitable time with reference to the position of the engine piston. In magnetos of the oscillating type with which I am familiar no good means 25 have been provided for advancing the time of producing maximum current from the generator after the engine has been started. It is the usual practice to start a stationary engine with the spark occurring beyond 30 'dead' center; that is to say, in retard position.

Certain attempts have been made to shift 35 the position of the spark after the engine has been started manually but on account of the method of connection of an oscillating type magneto to the engine, it is not easy to do this automatically. It is, therefore, another object of my invention to provide a simple, inexpensive means of advancing the 40 spark automatically after the engine has been started.

Other and further objects will be apparent 45 to one skilled in the art after a study of the specification and the annexed drawings, wherein—

Figure 1 is a view of a portion of the engine showing an engine driven member in operative relationship to the ignition generator.

Fig. 2 is a partial view of the ignition generator and certain engine members.

In the drawings, 1 illustrates an engine driven member which, in the case at hand, is the cam shaft gear mounted adjacent the 55 flywheel 2, 3 being a governor associated

with the parts 1 and 2 for governing the throttle of the engine. Carried on a bracket 4 is an ignition generator 5. An electrical conductor 6 extends from generator 5 to an insulated electrode in the engine cylinder. 60 These electrodes are not shown as they form no part of my invention and are well understood in their construction and operation and will, therefore, not be referred to in detail herein. The generator 5 has a shaft 65 7 which operates a rotatable member for the generation of electrical current. Fastened to the shaft 7 is a trip lever 8. Associated with the trip lever 8 are springs 9, having one end attached to an arm of the 70 trip lever and the other end attached to a suitable bearing 10, preferably carried on a bracket 11 fastened to the ignition generator. Carried on the engine driven member 1 is a cam member 12, the same being preferably supported on a pivotal bearing 13. A stop pin 14 limits the movement of the member 12 in one direction and the pin 15 limits its movement in the opposite direction. A pawl 16 is pivotally carried on the 75 member 1 by pivot screw 17. The pawl 16 has a nose 18 adapted to engage the notch 19 in the member 12 when the pawl has moved to the dotted position indicated at 20, the member 12 then being in the position shown by dotted lines 21.

In operation, when the engine is being started the member 12 is in the position shown in full lines in Fig. 1 and as the member 1 turns in the direction of the arrow, the cam member 12 will act on the trip lever 8 to move the rotatable member of the generator 5 to a position which will tension the springs 9 and when the rotation of member 1 has proceeded far enough the trip member 8 will slip over the nose of the cam 12 and the springs 9 will rapidly return the rotatable member of the generator 5 to normal position, generating a relatively heavy current in the winding of the generator 100 which current will be conveyed by conductor 6 to the spark plug or sparking electrodes that are operated by suitable engine mechanism (not shown) when a low tension generator is used. As soon as the engine comes 105 up to its normal running speed the pawl 16, due to its weighted end 22, will move out to the position shown in dotted lines 20 pushing the cam member 12 to the position shown in dotted lines 21 and the nose 18 110

will engage the notch 19 thereby holding the cam member 12 in advanced position until the engine speed has dropped to a point considerably below normal.

5 It will be seen that I have provided a very simple and inexpensive mechanism to do this work and it will be apparent that various changes may be made in the details without departing from the spirit of my invention and the scope of the appended claims.

Having thus described my invention, what I claim is:—

1. An ignition generator for internal combustion engines, having a rotatable member for the generation of electric current, an oscillatory member secured thereto, rotary non-oscillatory means on the engine for intermittently engaging and moving said oscillatory member through a portion of a revolution and then releasing it, means for returning the oscillatory member to normal position after said release occurs, and means including a weighted pawl on said engine for automatically advancing said engine operating means for the purpose described.

2. An ignition generator for internal combustion engines, having a rotatable member for the generation of electric current, an oscillatory member secured thereto, rotary non-oscillatory means on the engine for intermittently moving said oscillatory member through a portion of a revolution and then releasing it, means for returning the oscillatory member to normal position after said release occurs, and means including a weighted pawl on said engine for automatically advancing said engine cooperating means and holding said cooperating means in advanced position during normal running of the engine.

3. In combination an ignition generator for internal combustion engines having a rotatable member for the generation of electric current, an oscillatory trip lever fastened to said rotatable member for rotating the same, a rotary non-oscillatory engine driven member, a member for intermittently engaging and actuating the trip lever carried on said engine driven member, spring associated with said lever for returning the trip lever and rotatable member after being actuated by said actuating member, and a weighted pawl operated by the engine for moving said actuating member to advanced position as described.

4. In combination an ignition generator for internal combustion engines having a rotatable member for the generation of electric current, a trip lever fastened to said rotatable member for rotating the same, an engine driven member, a cam for actuating the trip lever pivotally mounted on the engine

driven member, springs associated with said trip lever set under tension by movement thereof, for quickly returning said trip lever and rotatable member after said trip lever has been released by said cam and a pawl carried on the engine member responsive to centrifugal force for moving the cam member to advanced position after the engine has been started.

5. In combination an ignition generator for internal combustion engines having a rotatable member for the generation of electric current, a trip lever fastened to said rotatable member for rotating the same, an engine driven member, a cam for actuating the trip lever pivotally mounted on the engine driven member, springs associated with said trip lever set under tension by movement thereof, for quickly returning said trip lever and rotatable member after said trip lever has been released by said cam and a pawl pivotally mounted on the engine member responsive to centrifugal force provided with means for automatically moving the cam to advance position after the engine has been started and for permitting the cam to return to retard position at a predetermined low speed of the engine.

6. In an ignition system, the combination of, an oscillating type of electric generator comprising a trip lever attached to the rotatable member of the generator and having springs for producing a quick impulse of the rotatable member after displacement and release thereof by the trip finger, a rotary non-oscillatory engine operated cam for actuating the trip lever and means responsive to the speed of the engine for advancing and holding the cam in an advance position during normal running of the engine.

7. In combination, an ignition generator for internal combustion engines having a rotatable member for the generation of electric current, a trip lever fastened to said rotatable member for rotating the same, an engine driven member, a cam for actuating the trip lever pivotally mounted on the engine driven member, springs associated with said trip lever set under tension by movement thereof, for quickly returning said trip lever and rotatable member after said trip lever has been released by said cam, a centrifugally responsive pawl pivotally mounted on the engine member and cooperative means on the pawl and cam member for moving the cam member to spark advanced position and for holding the cam member in such position, when the engine driven member has attained a predetermined angular velocity.

In testimony whereof, I affix my signature.
ALBERT ERICKSON.
